UNITED STATES PATENT OFFICE.

NATHAN E. TYRRELL, OF KANSAS CITY, MISSOURI.

OIL BURNER.

Application filed April 26, 1923. Serial No. 634,716.

To all whom it may concern:

Be it known that I, NATHAN E. TYRRELL, a citizen of the United States, and resident of Kansas City, county of Jackson, 5 State of Missouri, have invented a certain new and useful Improvement in Oil Burners, of which the following is a complete specification.

This invention relates to gravity oil burners and one of the objects is to produce a burner of such type that there will be practically no carbon produced when the burner is burning a normal quantity of oil, or when it is burning a very small quantity of oil.

Another object is to provide fixed means in combination with the oil burner whereby gas may be employed to ignite the burner and commence generation, and also may be burned simultaneously with the oil, if found desirable.

A further object is to provide means whereby the bowl of the burner may be readily and quickly leveled after the 25 burner has been installed in position within a furnace.

A still further object is to produce a burner of the character mentioned of strong, durable, efficient and inexpensive construction; and in order that it may be fully understood, reference is to be had to the accompanying drawing, in which:—

Figure 1 is a top plan view of an oil burner embodying the invention;

Figure 2 is a section on the line II—II of Figure 1; and

Figure 3 is a reduced side elevation of the burner.

In the said drawing, where like reference characters identify corresponding parts in all of the figures, 1 represents a circular base ring which is adapted to rest on the grate of a furnace or to be embedded in any suitable insulating material. The base ring 1 is formed with an external circumferential flange 2 near its upper end, and said flange is provided with suitable threaded openings in which are screwed a plurality of leveling screws 3, which support a dished and flanged base plate 4 formed with a series of air conduit openings 5 near its periphery. The base plate is also formed centrally with an upwardly projecting discharge nozzle 6 having internal threaded engagement with an oil supply pipe 7 projecting upwardly through the grate of the

furnace into the burner, the bore of the nozzle above the threaded portion thereof providing a receptacle 6^a forming a heating and partial vaporizing chamber. 60

In order to aid in positioning the base plate 4 on the ring 1, said plate is formed with a series of downwardly extending lugs 8 adapted to be received in notches 9 formed in the circumferential flange 2 of the base ring. In this connection it will be evident that the leveling screws 3, may be readily utilized to insure the even distribution of the oil, flowing from the nozzle, over the entire surface of the dished plate, 70 and when the oil is ignited and is burning, as will hereinafter appear, that the base ring 1 and the plate 4 conjointly form a heating chamber 10 for the air entering the burner, the heating of the air aiding materially in the vaporization of the oil.

The mouths of the air conduits 5 are formed with upwardly projecting shoulders 11 adapted to cooperate with shoulders 12 formed on the ends of tubular air conduits 80 13, said conduits converging centrally to the vertical axis of the burner to form a central air chamber 14, circumscribed by a downwardly extending flange 15. The nozzle 6 formed on the base plate extends 85 upwardly into the air chamber 14 and is received within an inverted cup 16 removably depending through an opening formed in the upper wall of the air chamber, said cup acting as a deflector for the air currents delivered through the conduits 13 and also as a heater of the partially vaporized oil due to the fact that the cup is directly exposed to the heat in the combustion chamber of the furnace and is also in direct 90 contact with the conduits 13.

The base plate 4 is formed with a suitable overflow opening 17, to drain off unconsumed oil and prevent the flooding of the furnace, and said plate is also formed with a circular rib 18 around the base of the nozzle to form a retaining and centralizing means for a thin metal ring or cylinder 19 resting on the plate, as clearly shown in the drawing, the top of the ring being higher 100 than the outer periphery of the plate and being exposed to the direct action of the flame to aid in the vaporization of the oil, as said ring will be heated rapidly and uniformly. In order to provide means for commencing 105 the generating action of the burner and also to provide means for burning gas in com-

bination with oil, a suitable gas pipe 20 is introduced into one of the conduits 13 through the grate of the furnace as common in the art.

- 5 In normal operation the oil will be vaporized by the heat of the cup 16 and the conical nozzle before it attains the base of said conical nozzle, but when the burner is first started, burning on a very small flame, or
 10 burning at full capacity, a small quantity of the oil may not be vaporized before it reaches the base of the nozzle, and this oil through contact with the ring 19 will be immediately converted into gas. The flame
 15 from the burner will be projected in all directions off the face of the plate 4 and against and between the conduits 13, thus highly heating the air in said conduits and chamber 10, before it mixes with the fuel to
 20 form a combustible mixture. By conduction the inverted cup 16 becomes highly heated and applies this heat at the point of overflow and thus materially assists in the gasification of the oil.
 25 It will also be apparent in this connection that the burner may be easily dismantled for cleaning purposes without the use of tools of any character, and that the oil feed pipe 7 if protected from direct contact with the
 30 flame and is, therefore, not subjected to becoming internally coated with carbon, as will be readily understood. It has been found in practice that this burner operates with great efficiency and little noise, and
 35 that the combustion is perfect regardless of the amount of fuel supplied, and hence is practicable for satisfactory use in moderate as well as severe weather. It will be noted that the provision of the gas supply pipe enables the burner to be maintained at a vaporizing temperature even though the supply of oil should be temporarily cut off.

From the above description it will be apparent that I have produced a gravity oil burner which embodies the features of advantage set forth as desirable in the statement of the objects of the invention, and which is obviously susceptible of modifications in various particulars without departing from the principle of construction and mode of operation involved.

I claim:

1. In an oil burner, a base plate, spaced air conduits leading from said base plate
 55 and converging toward a point centrally of and above said plate to form an air chamber

and being formed in their upper wall with an opening axially aligned with said plate, a vertical fluid nozzle carried by said plate in axial alignment with said opening, and an inverted tubular heat conducting element depending through said opening and supported by said conduits, the periphery of said element being spaced slightly from said nozzle.

2. In an oil burner, the combination of a base plate, a nozzle carried by and projecting above said plate, a series of air supply conduits converging together to form an air chamber above and surrounding said nozzle, and a vaporizing cylinder encircling the base of said nozzle and detachably carried by said plate and forming a closure adapted to retain oil; the cylinder being exposed to the direct action of the flame.

3. In an oil burner, a vertical oil supply nozzle, an air chamber surrounding said nozzle, and formed in its upper wall with an opening aligned with the axis of said nozzle, and an inverted tubular heat conducting element depending through said opening and supported by said upper wall of the air chamber, the periphery of said element being spaced slightly from the nozzle.

4. In an oil burner, a base plate, a combustion chamber, an oil supply nozzle projecting from said base plate into said combustion chamber, an upstanding rib formed on said base plate and encircling and spaced from the base of the nozzle and adapted for the retention of oil, a detachable cylinder resting on the base plate within said rib and being exposed to the flame and having its lower edge adapted to be immersed in the oil retained by said rib, means for supplying oil to the nozzle, and means for supplying air to the combustion chamber exteriorly of the detachable cylinder.

5. In an oil burner, a combustion chamber, a tubular heat conducting element depending therein, an oil supply nozzle located within the combustion chamber and slightly spaced from the periphery of the heat conducting element, a detachable cylinder encircling the base of the nozzle and exposed to the direct action of the flame, and means for supplying oil and air to the combustion chamber.

In witness whereof I hereunto affix my signature.

NATHAN E. TYRRELL.
